UNITED STATES PATENT OFFICE.

EMMA WORCESTER DOUGHTY, OF RAMAPO, NEW YORK, ASSIGNOR TO
CHENEY BROTHERS, OF SOUTH MANCHESTER, CONNECTICUT, A
CORPORATION OF CONNECTICUT.

DESIGN FOR TEXTILE FABRIC.

No. 37,613.

Specification for Design.

Patented Oct. 31, 1905.

Application filed August 26, 1905. Serial No. 275,972. Term of patent 3½ years.

To all whom it may concern:

Be it known that I, EMMA WORCESTER DOUGHTY, a citizen of the United States, residing at Ramapo, in Rockland county, State of New York, have invented a new, original, and ornamental Design for Textile Fabrics, of which the following is a specification, reference being had to the accompanying drawing, forming a part thereof.

The figure is a plan view of the fabric, showing my new design.

I claim—

The ornamental design for a textile fabric, as shown.

EMMA WORCESTER DOUGHTY.
